UNITED STATES PATENT OFFICE.

PAUL L. CROWE, OF BALTIMORE, MARYLAND.

CRUSHING APPARATUS.

Application filed October 20, 1925. Serial No. 63,744.

This invention relates to crushing apparatus and is directed more particularly to an apparatus for crushing ores, coal and similar material.

5 The primary object of the present invention is to provide a crushing apparatus which, while designed especially for use in connection with apparatus similar to that disclosed in my copending applications, 10 Serial No. 63,742 and Serial No. 63,743 filed of even date, shall also be useful in connection with any type of apparatus wherein a crushing of the material is to be effected.

15 A further object is to provide a crushing apparatus of this general character which shall be simple in construction, inexpensive to manufacture, and which shall be highly efficient and durable in operation.

20 With these and other objects in view, the invention may be stated to consist in the various novel features of construction and arrangement or combination, all of which will be fully described hereinafter and pointed out in the appended claims.

25 In the accompanying drawing, wherein I have shown certain illustrative embodiments of my invention, but without intent to limit myself thereto,

Fig. 1 is a vertical sectional view through 30 a crushing apparatus constructed in accordance with my invention;

Fig. 2 is a top plan view thereof;

Fig. 3 is an elevation of one of the crushing plates;

35 Fig. 4 is a top plan view of such plate;

Figs. 5, 6 and 7 are vertical sectional views, each of a modified form of crushing apparatus; and

40 Fig. 8 is a vertical sectional view of one element of a still further modified form of apparatus.

45 Describing the various parts by reference characters, and referring particularly to Figs. 1-4, inclusive, 1 denotes generally one of a pair of crusher plates which are pivotally mounted for oscillatory movement. Each plate is preferably identical in construction and shape so as to facilitate manufacture and replacement. As shown in Fig. 50 1, the side wall 2 of each plate is angular in shape and is provided with end walls 3 and 4 which extend from the top to a point slightly below the central angular portion thereof. Extending upwardly from the

angular portion of the plate on the inner 55 face thereof is a wear plate 5 which is secured in position by screws 6 or other suitable fastening means. The opposite face of each plate is reinforced by strengthening ribs 7 and 8 arranged vertically and horizontally, respectively. The side wall 3 of each plate is provided with an offset portion 10 so that a side wall 4 of an oppositely disposed plate will overlap the offset portion and present a smooth exterior surface. 60 The crushing plates are each provided with a pivot pin 11 that terminates in a spherical projection 12 and the offset portion on the opposite wall is formed with a slot 13 so when a pair of crushing plates are assembled in operative relation, the pin in each plate will engage in the slot in the other plate and thereby pivotally connect 65 said plates. A pair of springs 15 interposed between each spherical projection 12 and suitable abutments 16 carried by the framework of the apparatus, normally retains the crushing plates in operative relation. If, however, a lump of the material to be crushed is too hard to be broken by 70 the plates, the yielding connection between the plates will permit the same to open and thereby prevent damage to the apparatus. In this connection, it will be understood that where there is no such danger to the 75 apparatus due to the character of the material being crushed, the yielding connection could be dispensed with and the pivot pins engaged in an aperture instead of a slot, such modification being obvious, and hence 80 illustration thereof is deemed unnecessary.

The plates may be oscillated in any suitable manner, as for example, by a cam or eccentric 17 journaled between the downwardly and outwardly directed lower portions of the plates, such cam or eccentric being engaged by adjustable wear or contact shoes 18 that are carried by the plates. It will be noted at this point that, if desired, one of the plates may be held stationary, and the other plate above oscillated. 95

In operation, the material to be crushed is introduced into the hopper defined by the upper portions of the plates and power applied to the shaft carrying the cam or eccentric to rotate the same. The shoes 18 engage the cam and serve to oscillate each plate to cause the upper portions thereof to 100 105

advance toward, and then recede from each other and thereby effect a crushing of the material.

In Fig. 5, I have shown a modified form 5 of apparatus wherein the vertical strengthening ribs 7^a are made somewhat larger than those described in connection with Figs. 1-4. These ribs are provided one with an aperture 20 that is adapted to receive a pivot pin 10 21, and the other with an elongated slot 22 wherein the pivot pin 23 is yieldingly engaged by springs 24 interposed between said pin and end walls defining the slot. This arrangement serves to prevent damage to 15 the apparatus in event a particularly hard lump of material is encountered during the crushing operation, as such pivotal connection permits yielding between the plates. In this view also, I have illustrated the cam, 20 or eccentric, disposed at a greater distance from the pivot points of the plates, hence a greater leverage is obtained between the crushing jaws. In other respects, the apparatus is identical with that previously described.

In Fig. 6 I have illustrated a pair of crushing plates 26 pivoted at 27 and each provided with a downwardly directed portion 28 that terminates in an arcuate end 30 portion 29. A cam 30 arranged within the arcuate end portions is engaged by adjustable wear plates 18^a, as previously described.

In Fig. 7, I have shown a further modification wherein the plate oscillatory means 35 is arranged above the crushing jaws thereof. In this instance, each plate is provided with a downwardly directed portion 32 and an inwardly directed portion 33. The end walls 34 and 35 overlap, as in previous illustrations. An enlarged strengthening rib 36 is formed on each plate and suitable pivot pins 11^a and slots 13^a are formed in each end wall, or, if desired, these plates may be pivoted similar to that disclosed in connection 40 with Fig. 5 and as indicated in dotted lines. The upper end portion of each plate is provided with an adjustable screw 37 that is adapted to be engaged by a cam 38 to oscillate the plates about their pivot points 45 and thus effect a crushing action on the material introduced therebetween.

In Fig. 8, I have shown a still further modification, wherein each crushing plate 40 is formed with eccentric straps 41 at the 55 lower end thereof and such straps are provided with adjustable contact shoes 18^b for engagement with a cam or eccentric, not shown. Each plate is adapted to be pivoted at 42 and operates similar to those previously referred to.

In any of the foregoing illustrations, it will be understood that the cam or eccentric may be carried by a hollow shaft, a solid shaft or any other type of shaft, and such 60 shaft forms no part of the present invention.

What I claim is:—

1. A crushing apparatus of the character described comprising a pair of crushing plates having side walls arranged in overlapping relation, pins extending through 70 said walls for pivotally connecting said plates together, yielding means associated with said pins for holding said plates in normal pivotal relation but permitting said pivotal connection to yield and said plates to separate upon pressure in excess of normal, and means for oscillating said plates.

2. A crushing apparatus of the character described comprising a pair of crushing plates, each plate having a downwardly and inwardly directed portion defining a crushing jaw and a downwardly and outwardly directed portion defining a cam engaging plate, means for pivotally supporting said plates at points adjacent the apex of the angle defined by said portions, and a cam interposed between the downwardly and outwardly directed portions of said plates and adapted to engage both plates simultaneously to oscillate the same.

3. A crushing apparatus of the character described comprising a pair of crushing plates, each plate having a downwardly and inwardly directed portion defining a crushing jaw and a downwardly and outwardly directed portion defining a cam engaging plate, means for pivotally and yieldingly supporting said plates at points adjacent the apex of the angle defined by said portions, a single cam interposed between the downwardly and outwardly directed portions of 95 said plates, and an adjustably mounted wear plate carried by each plate and adapted to be engaged by said cam.

4. A crushing apparatus of the character described comprising a pair of crushing plates, each plate having a downwardly and inwardly directed portion defining a crushing jaw and a downwardly and outwardly directed portion defining a cam engaging plate, side walls carried by said plates, said side walls having offset portions arranged in overlapping relation, pivot pins extending through the overlapping portions of said side walls, and a cam disposed between said downwardly and outwardly directed portions and adapted to simultaneously engage both plates.

5. A crushing apparatus of the character described comprising a pair of crushing plates, each plate having a downwardly and inwardly directed portion defining a crushing jaw and a downwardly and outwardly directed portion defining a cam engaging plate, side walls carried by said plates, said side walls having offset portions arranged in overlapping relation, pivot pins extending through the overlapping portions of said side walls, means associated with said pivot pins for yieldingly retaining said 120 125 130

plates in normal crushing relation but permitting the pivotal connection between said plates to yield upon excessive pressure therebetween, and cam means interposed between the downwardly and outwardly directed portions of said plates for oscillating said plates.

6. A crushing apparatus of the character described comprising a pair of crushing plates, each plate having a downwardly and inwardly directed portion defining a crushing jaw and a downwardly and outwardly directed portion defining a cam engaging plate, side walls carried by said plates, said side walls having offset portions arranged in overlapping relation, pins extending through the overlapping portions of said side walls for pivotally connecting said plates, springs disposed on each side of said pins and engaged with a fixed abutment and said pins to yieldingly retain said crushing jaws in normal crushing relation, a cam interposed between said downwardly and outwardly directed portions, and adjustable

wear plates carried by the last mentioned portions of said plates and adapted to be engaged by said cam.

7. A crushing apparatus of the character described comprising a pair of oppositely arranged crushing plates each having side walls, a side wall of each of said plates having an offset portion adapted to overlap the side wall of the opposite plate, pins extending through the overlapping portions of said plates and pivotally connecting said plates together, springs interposed between said pins and a fixed abutment for yieldingly retaining said plates in normal crushing relation but permitting said plates to yield at their pivotal points upon excessive pressure therebetween, and a cam wheel interposed between said plates and having diametrically oppositely disposed cam portions adapted to engage said plates to effect an oscillatory motion of said plates.

In testimony whereof I affix my signature.

PAUL L. CROWE.
